Primary Examiner — Sheryl Lane*Assistant Examiner* — Ieisha N Price(74) *Attorney, Agent, or Firm* — Schneider IP Law LLC;
Laura Schneider(57) **CLAIM**

The ornamental design for a shovel, as shown and described.

DESCRIPTION

FIG. 1 is a perspective view of the shovel;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a back view thereof.

The broken lines in the drawings illustrate portions of the shovel and form no part of the claimed design.

1 Claim, 7 Drawing Sheets(56)
